CIGARETTE LIGHTER

Norbert Leopoldi, Chicago, Ill.

Application July 8, 1954, Serial No. 31,335

Term of patent 14 years

(Cl. D48—27)

To all whom it may concern:

Be it known that I, Norbert Leopoldi, a citizen of the United States and resident of Chicago, in the county of Cook and State of Illinois, have invented a new, original, and ornamental Design for a Cigarette Lighter, of which the following is a specification, reference being had to the accompanying drawings, forming part thereof.

Fig. 1 is a front elevational view of a cigarette lighter showing my new design;

Fig. 2 is a fragmentary front perspective view thereof; and

Fig. 3 is a rear perspective view, the cap being shown in closed position.

I claim:

The ornamental design for a cigarette lighter, substantially as shown.
